(57) CLAIM

The ornamental design for a fabric with pattern, as shown and described.

DESCRIPTION

FIG. 1 is a top plan view of a fabric with pattern according to a first embodiment of the design; and, FIG. 2 is a top plan view of a fabric with pattern according to a second embodiment of the design.

The dot-dash broken line perimeter surrounding the fabric with pattern in FIGS. 1 and 2 is for illustrating the boundaries of the claimed design only and does not form part of the claimed design.

1 Claim, 2 Drawing Sheets
